REGENERATIVE COKE OVEN

Hermann Petsch, Recklinghausen in Westphalia,
GermanyApplication January 19, 1937, Serial No. 121,365
In Germany January 20, 1936

4 Claims. (Cl. 202—144)

This invention relates to regenerative coke ovens. Such ovens are usually heated by passing the combustion constituents, gas and air, upwards into a group of the heating flues in each 5 heating wall and conducting the gaseous products of combustion downwards through a further group of the flues. The direction of the heating gases is subsequently reversed so that after reversal the combustion constituents now pass 10 through the group of heating flues through which the combustion products previously passed and vice versa. Those heating flues which, at any time, are being heated i. e. receive the combustion constituents, are connected with a corresponding group of regenerator chambers which, when rich gas is used, preheat the air 15 for combustion, and which, when poor or lean gas is used, preheat both the gas and the air. In a similar manner the heating flues through 20 which the products of combustion flow are also connected with regenerator chambers. When a number of individual regenerators are used and arranged under the oven soles to extend transversely to the oven battery, they are all divided 25 into halves by a wall, which runs across them. With tunnel-like regenerators which extend in the direction of the length of the battery, i. e. transversely to the oven chambers, a similar 30 dividing wall in the middle part of the oven itself is usual. With these known arrangements the vertical heating flues are usually connected with the corresponding regenerator chambers either directly or with the interposition of horizontal sole flues which extend under the chamber sole level. When the heating flues of the 35 entire heating wall as well as the associated regenerators are in each case subdivided lengthwise into halves which terminate in the middle of the wall, such connection between the regenerators and the heating flues gives rise to no 40 difficulties. If, however, the heating flues are grouped so that the wall is divided into more than two sections and reversal of flow takes place within each section, i. e. each of the two groups of heating flues in which the direction of gas flow is different is still further sub-divided, then in the said regenerator arrangements it is 45 the usual practice for each pair of sole flues which are associated with the two groups of heating flues and which extend over the entire length of the heating wall, to be arranged horizontally and one over the other; then one sole flue of a pair conducts a combustion medium, gas 50 or air, which rises into the heating flues, whereas the other sole flue located either above or

below the former flue conducts the waste gases to the regenerators. It is, however, a disadvantage that of the pair of sole flues disposed one over the other and which are necessarily separated only by a relatively slight partition, in 5 every case one flue contains ascending gases and the second flue descending gases. Owing to the differences in pressure between the ascending and the descending gases leakage through the partition may easily occur, and it is then impossible to prevent the medium in one sole flue 10 from passing to the adjacent sole flue.

It is the main object of the present invention to construct a regenerative coke oven of the kind mentioned, i. e. with periodic reversal of draught 15 in the heating wall, in such a manner that the above described disadvantage is absent. To this end in a coke oven according to the invention a pair of sole flues which are disposed one above the other and which extend over substantially 20 the whole length of the heating wall are arranged in combination with regenerators, which preferably extend transversely to the length of the oven battery and which are separated by a wall located at the middle part of the oven 25 chambers and running parallel with the length of the battery.

In such an arrangement the invention consists in connecting the regenerators with the heating flues in a heating wall in such a manner that 30 both sole flues connect the same group of heating flues with the associated regenerators so that the two flues at any time either both conduct media for combustion only, or the products of combustion only, according to the direction of gas 35 flow along the heating wall.

Other objects and advantages of the invention will be apparent from the following description of an example of a coke oven constructed according to the invention, and from the accompanying drawings in which is shown a horizontal compound coke oven having vertical heating flues arranged together in pairs and sometimes described as "twin flues," and also having regenerators which are arranged beneath the chamber sole level and which extend transversely 40 to the longitudinal direction of the battery.

In the accompanying drawings Fig. 1 is a vertical longitudinal section which in the upper half of the figure passes through the whole of the 50 heating wall, along the broken line A—B of Fig. 2. Fig. 2 shows in an enlarged scale a composition of five different vertical cross-sections, which correspond to the section lines C—D, E—F, W—X, G—H, and Y—Z of Fig. 1. Fig. 3 55

is a horizontal section along the line J—K of Fig. 1, that is exclusively through the regenerators. Fig. 4 is a plan comprising three different horizontal partial sections along the broken line L—M—N—O—P—Q of Fig. 2.

The heating walls located between the oven chambers 1 (Fig. 2 and Fig. 4) comprise a group of vertical heating flues 2 and a second group of heating flues 3 arranged to alternate with the flues 2, pairs of the flues 2 and 3 being interconnected at 4, to form a number of units or "twin flues." Below each heating wall there are located the rich-gas distributing channels 5 and 6, both of which extend over the entire length of the heating wall, and of which the passage 5 is connected by the nozzles 7 with the heating flues 2 and the passage 6 by the nozzles 8 with the heating flues 3. The gas distributing channel 5 is fed with rich gas through the feed main 9 which extends along the entire oven battery on its one side, and the gas distributing channel 6 through the similar feed main 9a disposed on the other side of the battery. Furthermore, below the heating wall there are provided sole flues 10 and 11, and 10a and 11a, disposed one over the other in pairs and extending the entire length of the heating wall. As shown in Fig. 2, a pair of flues 10, 11 and another pair 10a, 11a lie parallel to each other, each flue being associated, independently of the other, with the adjacent heating wall. The unbroken or continuous sole flues 10 (10a) are each connected respectively by vertical channels or shafts 12 (12a) with regenerator chambers 13 (13a) disposed beneath them which in their turn are connected respectively by way of the regenerator-sole flues 14 (14a) and the ducts 15 (15a) to poor gas feed mains 16 (16a) running along the battery sides. At the same time the regenerator sole flues 14 (14a) are respectively connected through reversing valves 23 (23a) with the collecting flues 20 (20a) for carrying off the waste gases, so that the connections between the sole flues 14, 14a and the flues 20, 20a respectively can be closed at will. The sole flues 11 (11a) are each divided respectively into two separate sections by the said shafts 12 (12a) and therefore are connected respectively by two obliquely upwardly directed passages 17 (17a) with the regenerator chambers 18 (18a) which run parallel to the regenerator chambers 13 (13a). The regenerator sole flues 19 (19a) provide the appropriate connection between the regenerators 18 (18a) and the outer air by way of the reversing valves 23 (23a) or with the chimney by way of the waste gas flues 20 (20a). The foregoing numerals provided with the letter a denote in each case the structural members of the oven in which the direction of the draught is in each phase a reverse one.

The regenerators arranged below the sole level are divided by a central transverse wall 27 into halves to form the regenerators 13, 18 and 13a. In the one direction of the draught, the regenerators 13 and 18 will carry poor heating gas and air for combustion while the regenerators 13a and 18a will carry the products of combustion. In each of the two halves of the oven gas regenerators 13, 13a alternate with air regenerators 18, 18a. Regarding the two opposite oven halves, a gas regenerator 13 will always face an air regenerator 18a, and so on. The arrangement is shown in Fig. 3, and such a section of the entire battery as shown in this figure which contains on each half of the oven four symmetrical ly disposed regenerator chambers, may be re-

garded as an operative unit which serves two adjacent heating walls of the battery in the manner explained.

According to the example of an embodiment shown in the drawings the combustion media preheated are distributed into the heating flues at various levels. With this object in view the sole flues 10 and 11 are connected respectively by branch passages 21 and 24 with vertical channels 23 and 26 arranged in the transverse partitions 22 and 25 of the heating walls, each channel being provided with a plurality of outlets, arranged at different levels, to the heating flues 2. The arrangement is such that in each case the vertical channels 23 of the partitions 22 are connected with the sole flues 10 and the regenerator chambers 13, but the vertical channels 26 of the partitions 25 which are sandwiched between the partitions 22 are connected with the sole flues 11 and the regenerator chambers 18. Similarly the sole flues 10a and 11a are connected respectively by corresponding branch passages 21a and 24a with a second series of vertical channels 23a and 26a arranged in the same partitions 25 and 22, each of said channels being provided with a plurality of outlets, arranged at different levels to the heating flues 3. The channels 23a in the partitions 25 are arranged at the side of the channels 26 and the channels 26a in the partitions 22 at the side of the channels 23. The channels 23a are connected with the sole flues 10a and the regenerator chambers 13a and the channels 26a with the sole flues 11a and the regenerator chambers 18a.

The mode of operation of the described coke oven, when heating with preheated poor gas is as follows:

The poor gas passes from the main pipe 16 through the branch pipes 15 and the regenerator sole flues 14, into the regenerator chambers 13 and is preheated therein. It then passes from each individual regenerator chamber 13 through the shaft 12 into the sole flue 10 and is further conducted through the branch passages 21 and the channels 23 of the partition walls 22 into all the heating flues 2 of the heating wall entering the flues at four different levels in the embodiment shown. The air for combustion is fed through the regenerator sole flues 19 to the regenerator chambers 18, and after being preheated, is conducted from each individual chamber 18 through the two passages 17 (see Fig. 1) into the subdivided sole flue 11, whence it is introduced through the branch passages 24 and the channels 26 of the partition walls 25 into all the heating flues 2 entering the latter at four different levels as shown. After combustion has taken place in the ascending heating flues 2, the gases of combustion enter by way of the passages 4 downwards the heating flues 3, and therefrom one part of the waste gases passes by way of the channels 23a of the partition walls 25 (see Fig. 4), the branch passages 21a, the sole flues 10a into the regenerator chambers 13a and thence through the regenerator sole flues 14a into the waste gas flue 20a of the battery. Another part of the waste gases passes from the heating flues 3 through the ducts 26a in the walls 22 (see also Fig. 4), the branch passages 24a, the sole flues 11a into the regenerator chambers 18a and thence by way of the regenerator-sole flue 19a also into the waste gas flue 20a. The general coupling of the several regenerator chambers as to the ways of poor heating gas, air and waste gases is explained by the leading arrows in Fig. 75

3. When in the alternating phase the direction of flow is reversed and the combustion media are conducted in the opposite direction.

According to the above description of the mode of operation the sole flues disposed in parallel side by side and one over the other, are so disposed and used in each operative phase that, for example,—cfr. Fig. 2—of the four sole flues 10 and 11, which can be seen lying adjacent to one another, the upper pair 10 conducts preheated heating gas, and the lower pair preheated air, while the other flues 10a and 11a all conduct waste gas, that is to say all these latter only one and the same medium. Thus everywhere in adjacently situated flues there flow only combustion substances having the same pressure, so that undesired overflow due to leakage between adjacent flues is prevented. Likewise the Fig. 2 shows that the two pairs of sole flues which are connected to any one heating wall and operated by reversal of draught, for example the pair 10 and 11 leading gas and air respectively on the one hand and the pair 10a and 11a leading waste gases on the other hand, are situated remote

from each other; on account of this arrangement, the different gas pressures prevailing in said two systems of flues make no matter. Adjacent spaces in which there is difference in pressure are only the lower sole flues 11 or 11a with regard to the regenerator chambers below them in case the former conduct air and the latter carry waste gases. In this case, however, in the event of leakage of the horizontal partitions between these flues and the regenerators, at the utmost only slight quantities of the air of combustion (but not heating gas) can pass into the waste gas being discharged, and this is not a serious disadvantage or loss.

For the mode of operation, which is also possible with the described coke oven, and in which heating is effected by rich heating gas all the regenerators are arranged to preheat air with reversal of draught as described, and the rich gas is fed in each case through one of the two distributing channels 5 or 6, also with reversal of flow.

The coke oven described above may be modified in such a manner that of the two combustion media, gas and air, only one is distributed in the vertical direction by stages while the other medium is introduced directly and solely into the bottom of the heating flue. In this case each of the partition walls 22 and 25 would contain only one vertical channel for one combustion medium, while it is intended that the second combustion medium should be fed in approximately the same manner, as described below, when vertical channels are omitted or abbreviated. Instead of one vertical channel in each single wall, pairs of vertical channels could be arranged in alternate partition walls only.

In a still further simplified form of construction it may be provided that the preheated heating gas and also the preheated air for combustion—for producing the ordinary single stage heating, which is very usual particularly with twin heating flues—are conducted merely to the bottom of each heating flue. With the embodiment shown in the drawings this can be done without any alteration of the whole of the passage system, in that of each vertical duct 23, 23a, 26, 26a only the bottom one of the four superposed outlets (Figs. 1 and 2) are allowed to remain, the part of each vertical duct above this outlet being omitted. This means that the sole

flues 10 and 11 are connected directly to the bottom parts of the heating flues 2 and the sole flues 10a and 11a directly to the bottom parts of the heating flues 3 by simple short intermediate passages or nozzles.

With coke ovens having twin-flues, because of the reversal of gas flow, it must be always arranged that each vertical channel in the partition walls has its outlets for the combustion medium directed only towards one adjacent heating flue and not towards both. The invention is not, however, limited to the use of twin heating flues, such as shown in the drawings. Instead the entire heating wall may also be divided in such a manner that each individual section consists of a plurality of heating flues for upward passage of gases and a plurality of heating flues for downward passage of gases, which cooperate upon reversal of draught. The only case excluded is that in which the entire heating wall is divided lengthwise in the usual manner into two halves abutting in the middle of the wall and which operate with reversal of draught.

What I claim is:

1. A regenerative coke oven battery arranged to operate with periodic reversal of the direction of flow of the gases through the heating spaces of the oven battery, comprising a plurality of oven chambers, a heating wall adjacent each said chamber, heating flues within each said wall, pairs of sole flues with the flues of each pair adjacent to and arranged one above the other, all of said flues of both pairs being closely grouped together in such relationship, ducts connecting the single flues of each said pairs respectively with one heating wall and opening into certain heating flues thereof which are distributed over the whole length thereof, further pairs of sole flues widely spaced from the first mentioned group of sole flues with the flues of each pair adjacent to and arranged one above the other and with all of the flues of said further pairs of sole flues also closely grouped together in the particular relationship mentioned, ducts connecting the single flues of said last-mentioned pairs respectively with heating flues other than the last-mentioned heating flues in the same heating wall, a dividing wall extending over the whole battery and positioned transversely to the oven-chambers, regenerator chambers on one side of said dividing wall, means for supplying poor gas and air for combustion respectively to alternate ones of said chambers, means connecting each of said alternate chambers respectively to one of the sole flues of the first-mentioned pairs, further regenerator chambers on the other side of said dividing wall and oppositely disposed to the first-mentioned regenerator chambers, said further regenerator chambers being similarly arranged and connected to the further pairs of sole flues, and all said first-mentioned regenerators cooperating with the last-mentioned regenerators by periodic reversal of draught.

2. A regenerative coke oven battery as claimed in claim 1 in which regenerator chambers on one side of the dividing wall which are arranged to receive poor gas in one phase of operation are oppositely disposed to regenerators on the other side of the dividing wall which are arranged to receive air for combustion in the other phase of operation following the reversal of draught.

3. In a regenerative coke oven having heating walls containing a number of heating flues, a pair of sole flues arranged one vertically above

the other and provided with means for connecting these sole flues with one group of heating flues distributed along the whole length of a heating wall, a second pair of sole flues likewise arranged one above the other but widely spaced from the flues of the first mentioned pair and provided with means for connecting these latter sole flues with another group of heating flues distributed along the whole length of the same heating wall, the sole flues of the first pair being each connected respectively with a single regenerator chamber which latter extends parallel with and below the oven and both serve for simultaneous supply of combustion constituents or simultaneous discharge of combustion products and the sole flues of the second pair being likewise respectively connected in similar manner as the first pair with other regenerators which are arranged to cooperate with the first-mentioned regenerators by periodically reversing the direction of draught.

4. A regenerative coke oven having regenerators arranged below the sole level of the oven and separated into halves by a wall extending

transversely to the oven chambers, a pair of sole flues disposed adjacent to and one vertically above the other and each opening to a number of heating flues spaced over the whole length of a heating wall and to a pair of regenerators, and a further pair of sole flues disposed adjacent to and one vertically above the other and arranged parallel to but widely spaced from the flues of the first pair which each open to the remaining heating flues in the heating wall and to another pair of regenerators, the arrangement being such that one pair of sole flues provides the connection with one group of heating flues and with regenerators positioned in one half of the oven and the other pair of sole flues provides the connection with a further group of heating flues and with regenerators positioned in the opposite half of the oven, the regenerators in the one oven half being arranged to cooperate with the regenerators in the other oven half by periodically reversing the direction of draught.

HERMANN PETSCH.
